UNITED STATES PATENT OFFICE.

OLIVER FIKE, OF MADISONVILLE, KENTUCKY.

SCRAPER.

1,420,919.

Specification of Letters Patent. Patented June 27, 1922.

Application filed January 28, 1921. Serial No. 440,678.

To all whom it may concern:

Be it known that I, OLIVER FIKE, a citizen of the United States, residing at Madisonville, in the county of Hopkins and State 5 of Kentucky, have invented a new and useful Scraper, of which the following is a specification.

The device forming the subject matter of this application is adapted to be employed 10 for removing dust from a hole which has been bored in a coal mine to receive an explosive charge.

The invention aims to provide novel 15 means for operating and controlling a blade, which, being mounted pivotally, at one end of a staff, serves to engage the dust.

I do not bind myself to the specific form shown, since, within the scope of what is claimed, a mechanic may make changes without departing from the spirit of the invention.

In the drawings:—Figure 1 shows in front elevation, a tool constructed in accordance with the invention, the blade being 25 disposed parallel to the staff; Figure 2 is a side elevation wherein parts are broken away; Figure 3 is a section on the line 3—3 of Figure 2; Figure 4 is a fragmental elevation showing the blade disposed at right angles to the staff.

The numeral 1 denotes a staff of any desired length, the length of the staff being governed by the depth of the holes, on an average. At one end, the staff 1 is supplied 35 with a handle 2. The opposite end of the staff 1 terminates in a thinned part 3 received between ears 4 on a blade 5, the elements 3 and 4 being connected by a pivot member 6, the construction being such that 40 the blade may be disposed parallel to the staff 1, as shown in Figure 1, or at right angles thereto, as shown in Figure 2. Guides 7 and 8 are mounted on that portion of the staff 1 which is adjacent to the handle 2. 45 Guides 9 are distributed along the staff 1 between the guide 8 and the blade 5.

The device includes an operating member denoted generally by the numeral 10. The operating member 10 is a composite structure, 50 embodying a rigid plunger 11, mounted to reciprocate in the guides 7 and 8. At one end, the plunger 11 is supplied with a handle 12, so located that it may be grasped in one hand, along with the handle 2 on the 55 staff 1. The plunger 11 is supplied with a notch or seat 14. A latch 15 is pivotally

supported as shown at 16 on the guide 7 and includes a projection 17 adapted to be engaged in the notch or seat 14. A spring 18 is secured at one end to the latch 15 and 60 bears at its other end on the plunger 11. The function of the spring is to cause the projection 17 of the latch 15 to bear on the plunger 11, so that when the plunger 11 is retracted, the projection on the latch will 65 engage automatically with the seat 14, as depicted in Figure 2.

The operating member includes, further, a connection 19 which may be in the form of a rod having some flexibility or resiliency, 70 the connection being mounted to reciprocate in the guides 9. The connection 19 is pivoted at one end, as shown at 20, to a projection 21 on the blade 5. The opposite end of the connection 19 is united by pivot element 23 with the inner end of the plunger 11. A compression spring 24 surrounds a portion of the plunger 11, one end of the spring engaging a washer 25, which, in its turn, bears against the guide 8, the other 80 end of the spring engaging a washer 26 which abuts against the pivot element 23. It may be noted that the pivot element exercises a double function, in that it constitutes a connection between the parts 19 and 11, 85 and forms, as well, an abutment for the spring 24.

In practical operation, the blade 5 is disposed parallel to the staff 1, as shown in Figure 1, the spring 24 serving to advance 90 the operating member 10, and to hold the blade parallel to the staff. The working end of the tool may be introduced into the drill hole, the blade 5 entering the dust readily, because the blade is located parallel to 95 the staff 1 and parallel to the line of advance of the staff, when the staff is thrust into the hole. After the blade 5, arranged as shown in Figure 1, has been worked into the hole to the desired point, the operator 100 retracts the plunger 11, and consequently the connection 19, by means of the handle 12, until the blade 5 is at right angles to the staff 1, the projection 11 on the latch 15 engaging the seat 14 in the plunger 11 to hold the blade 5 in the position shown in Figure 2, and to prevent the operating member 10 from advancing under the action of the spring 24, which has been compressed. The staff 1 is retracted out of 110 the hole, the blade 5 carrying the dirt or dust. Pressure exerted on the latch 15 dis-

engages the latch from the seat 14, whereupon the parts are restored to the position of Figure 1, under the impulse of the spring 24.

5 I claim:—

1. In a device of the class described, a staff; a blade pivoted to the staff; an operating member slidable on the staff and pivoted to the blade; spring means for advancing the operating member; and releasable means for holding the operating member retracted, against the action of the spring means.
2. In a device of the class described, a staff; a blade pivoted to the staff; an operating member slidable on the staff and pivoted to the blade; spring means for advancing the operating member; a latch supported for swinging movement and coacting with the operating member to hold the same retracted against the action of the spring

means; and a spring interposed between the latch and the operating member and constituting means for engaging the latch with the operating member.

25

3. In a device of the class described, a staff; a blade pivoted to the staff; a guide on the staff; an operating member slidable in the guide and pivoted to the blade; spring means for advancing the operating member; and a latch pivotally mounted on the guide and coacting with the operating member to hold the same retracted against the action of the spring means.

30 In testimony that I claim the foregoing as my own, I have hereto affixed my signature in the presence of two witnesses.

OLIVER FIKE
